UNITED STATES PATENT OFFICE.

THOMAS P. COLE, OF MEMPHIS, TENNESSEE.

GEARING FOR MOTOR-BOATS.

968,128.

Specification of Letters Patent. Patented Aug. 23, 1910.

Application filed June 25, 1909. Serial No. 504,295.

To all whom it may concern:

Be it known that I, THOMAS P. COLE, a citizen of the United States, residing at Memphis, in the county of Shelby and State of Tennessee, have invented certain new and useful Improvements in Gearing for Motor-Boats, of which the following is a specification, reference being had therein to the accompanying drawing.

10 This invention relates to propelling mechanism for motor boats, and the principal object of the same is to provide a novel type of driving mechanism for the propeller by means of which the operation of the propeller may be controlled, and also to provide means whereby the propeller may be utilized as a rudder.

In carrying out the objects of the invention generally stated above it will, of course, be understood that the essential features thereof are susceptible of changes in details and structural arrangements, but a preferred and practical embodiment thereof is shown in the accompanying drawings, wherein—

25 Figure 1 is a longitudinal sectional view of the stern of a boat, showing the improved driving and steering gear applied thereto. Fig. 2 is a horizontal sectional view taken on the line 2—2, Fig. 1. Fig. 3 is a detail end 30 elevation of the boat. Fig. 4 is a detail fragmentary view of the main power shaft and one of the loose gear wheels thereon showing the manner of locking said shaft to said gear.

35 Referring to said drawings by numerals 1 designates a portion of a boat's stern, the flooring of which carries an end bearing 2 for a main power shaft 3 extending longitudinally of the boat. Said shaft is in sections which are held in slidable engagement by means of a clutch sleeve 4. A shifting lever 5 is pivotally mounted on said flooring adjacent to said shaft and carries a cam 6 at its lower portion which engages between 45 two collars 7 and 8 fast on said shaft so that when the said lever is rocked, the said shaft will be shifted longitudinally. The rear end of the main power shaft has loosely mounted thereon two bevel gears 9 and 10, 50 which are disposed on opposite sides of the bearing 2, and each gear carries an outstanding laterally projecting lug 11 which is adapted to be selectively engaged by either of the lugs 12 or 13 projecting laterally from 55 the shaft 3.

A vertically arranged shaft 14 projects

through bracket bearings 15 projecting from the stern of the boat, the lower end of said shaft 14 extending into a casing 15 which incloses the gears 9 and 10, and carries a 60 bevel gear 16 which is in mesh with said gears 9 and 10. The upper end of said shaft 14 extends into a casing 17 and carries a bevel gear 18 which is in mesh with a similar gear 19 carried by a horizontal shaft 20 65 mounted in bearings 21 carried by the upper edge of the stern and which projects beyond said stern and enters a casing 22. A bevel gear 23 is mounted on said shaft 20 within said casing 22, said gear being in mesh with a similar gear 24 carried by the upper end of a vertical shaft 25 the lower end of which projects into a casing 26 having a bottom socketed extension 27 in which a pivotal end 28 of a bracket arm 29 is mounted, said 75 bracket arm 29 projecting from the skeg 30. The end of said shaft 20 within the casing 26 carries a bevel gear 31 which is in mesh with a similar gear 32 on the end of a shaft 33 which projects through the said casing 26 and has its outer end journaled in a bearing 34 of a propeller housing 35, one end of which is secured to a tube 36 the upper end of which has a rotatable engagement with the casing 22 and whose lower end has a 80 threaded engagement with the casing 26. The lower end of said housing is connected with the socketed extension 27 of said casing 26. A propeller 37 is mounted on the shaft 33 within the propeller housing 35. 90 The tube 36 surrounds the shaft 33 and has its upper end mounted in a bracket bearing 38.

A steering lever 39 is mounted within the boat and has a pivotal connection with a rack 40 which is engaged by a pawl and lever 41. A rod connection 42 extends from the steering lever to a crank or tiller arm 43 projecting from the tube 36.

It will be obvious from the foregoing that by rocking the lever 5 forwardly the gear 10 will be locked to the shaft 3 and caused to rotate therewith thereby imparting its movement to the shaft 14 which in turn is communicated to the shaft 20, which in turn 100 communicates its movement to the shaft 35, and the latter shaft communicates its movement to the propeller shaft. The movement just described imparts a forward movement to the propeller. To reverse, the lever 5 is 105 rocked rearwardly which causes gear 9 to be locked to the shaft 3, and thereby impart a 110

reverse movement to the shafts 14, 20, 35 and the propeller shaft. To disconnect the said gears 9 and 10, the lever 5 is brought to the vertical position shown in Fig. 1. To 5 steer the boat, the lever 39 is rocked either forwardly or rearwardly, which communicates its movement to the rod 42, and the latter actuates the arm 43 which causes the tube 36 and the casing 26 to turn and therefore 10 by throw the propeller to either the right or left and thereby steer the boat, as will be readily understood.

While in the foregoing description and the accompanying drawings the steering mechanism has been shown as provided with a lever for operating the same, it will, of course, be understood that other means for operating the same may be used if desired.

What I claim as my invention is:—

- 20 1. A driving and steering mechanism for boats, comprising a main power shaft located within the boat, a propeller shaft exterior of the boat, a propeller thereon, a vertically disposed shaft operated by the main power shaft, a horizontally arranged shaft operated by the vertical shaft and projecting beyond the boat, a vertically arranged shaft exterior of the boat and operated by said horizontal shaft, a gear connection between the last mentioned vertical shaft and the propeller shaft, a housing inclosing the propeller shaft and propeller, a bracket for pivotally supporting said housing, and means for shifting said housing to cause the propeller to steer the boat.

2. A driving and steering mechanism for boats comprising a main power shaft within a boat, reversing mechanism carried thereby, a vertical shaft operated by and connected with said reversing mechanism, a horizontal shaft operated by said vertical shaft, a vertical shaft exterior of the boat and operated

by the horizontal shaft, a tube surrounding the last-mentioned vertical shaft, a casing carried by the lower end of the tube and into which said shaft projects, a bracket arm projecting from the boat and having a pivotal connection with said casing, a propeller housing having one end connected to said tube and its other end connected with said casing, a propeller shaft within said housing and projecting into said casing, a gear connection between said propeller shaft and the end of the vertical shaft within said casing, a propeller on the propeller shaft, and means connected with said tube for shifting said housing, casing and propeller and shaft to steer the boat.

3. A steering and driving mechanism for boats comprising a main power shaft within a boat, a vertically disposed tube exterior of the boat, a casing projecting from the bottom of said tube, a pivotal connection between said casing and the boat, a propeller shaft having one end entering said casing, a shaft extending through said tube and into said casing for operating the propeller shaft, means operated by the main power shaft for operating the shaft within said tube, a propeller on the propeller shaft, a housing for the propeller and shaft, said housing having one end connected to said tube and the other end connected with said casing, a crank arm projecting from said tube, a shifting lever within said boat, and a rod connection between said crank arm and said shifting lever.

In testimony whereof I hereunto affix my signature in presence of two witnesses.

THOMAS P. COLE.
